(57) **CLAIM**

The ornamental design for a “combination gas valve wrench and water valve wrench”, as shown and described.

DESCRIPTION

FIG. 1 is a front elevational view of a combination gas valve wrench and water valve wrench, showing my new design, the rear elevational view being a mirror image thereof; FIG. 2 is a right side elevational view thereof; FIG. 3 is a left side elevational view thereof; FIG. 4 is a top plan view thereof; and, FIG. 5 is a bottom plan view thereof.
